UNITED STATES PATENT OFFICE.

ISRAEL KINNEY, OF DETROIT, MICHIGAN, ASSIGNOR TO JOSEPH S. STOCKWELL, EDWARD M. WEATHERHEAD, FREDERICK W. DURRANT, AND EDWARD F. H. PEARSON.

COMBINED FOOT SCRAPER AND WIPER.

SPECIFICATION forming part of Letters Patent No. 605,552, dated June 14, 1898.

Application filed February 14, 1898. Serial No. 670,229. (No model.)

To all whom it may concern:

Be it known that I, ISRAEL KINNEY, a subject of the Queen of Great Britain, residing at Detroit, in the county of Wayne and State of Michigan, have invented certain new and useful Improvements in a Combined Foot Scraper and Wiper; and I do hereby declare the following to be a full, clear, and exact description of the invention, such as will enable others skilled in the art to which it appertains to make and use the same, reference being had to the accompanying drawings, forming a part of this specification.

This invention relates to new and useful improvements in a combined foot scraper and wiper; and it consists in the construction and arrangement of parts, as hereinafter fully set forth, and pointed out particularly in the claim.

20 The object of the invention is to procure a combined foot scraper and wiper that will be cheap, simple, and durable, and one wherein the greater portion of the dirt on one's feet may be scraped off and the remainder wiped onto the wiping material at the side of said scraper, thus enabling the shoes to be thoroughly cleaned and the wiper to be kept clean for a considerable length of time, which object is attained by the construction and association of parts illustrated in the accompanying drawings, in which—

Figure 1 is a perspective of my improved foot scraper and wiper complete. Fig. 2 is an enlarged bottom plan of same. Fig. 3 is a perspective view of the scraper and frames for retaining the wiping material, said material being removed. Fig. 4 is a transverse section through the bar and side rails of the frame for retaining the fibrous wiping material in place.

Referring to the letters of reference, A designates a rectangular plate. At the back of said plate and extending at right angles therefrom is a blade or scraper B, said plate being provided with suitable apertures α , through which screws, nails, or other devices may be passed to secure said plate in place.

At each end of the plate A and on a plane therewith is a rectangular frame C, said frame having the center of its end pieces raised, and

a bar D, extending centrally over the opening in said frame from the raise on one end piece to the raise on the other. For cheapness of construction I form the plate A, scraper B, frame C, and bar D integral by 55 casting said parts in one piece.

E designates sections of rope, cut the proper length, which are doubled upon their center and passed up from the under side of the frame, with one end of said bent sections on 60 either side of the bar D, as clearly shown in Fig. 4. This operation is continued until the space between the ends of the frame C is filled with such sections, when the portions that extend over the side rails of the frame 65 are untwisted or frayed out into shreds until the fiber of the rope-sections is completely changed from the former compressed condition. The only part of the rope-sections that retain their former appearance and form is 70 that which extends across the frames C and under the bar D, as clearly shown in Fig. 2. After the rope-sections have been untwisted it will be impossible to withdraw them from the frame, as the untwisted ends of said sections occupy a greater space and are too bulky to be drawn out of the frame, and when the loosened ends of the fiber have become intertwined in its shredded condition it is impossible to withdraw a single 75 strand. Should the wiping material become wet, the sections of the fibrous material that extend under the bar D and over the sides of the frame will become expanded by absorbing moisture and the more tightly bind 80 said fibrous material in place in the frame, as will be well understood.

It will now be seen that by employing the parts comprising this improved foot scraper and wiper associated in the manner set forth 90 a very useful and durable article is produced, the parts being few and substantial, and there is nothing to get out of order, and after it has once been located will serve for a long time, as it can easily be cleaned when desired. 95

By raising the bar D above the plane of the side rails of the frame C that portion of the rope-sections which extend under said bar will be above the lower surface of said frame and plate A, thereby enabling said 100

plate to be fastened down tightly on an even surface. In some variations of the frame C, however, said bar D is located in the same plane as the side rails of the frame C.

5 Having thus fully set forth my invention, what I claim as new, and desire to secure by Letters Patent, is—

In a foot scraper and wiper, the combination of the plate, the scraper on said plate, the frame at the end of said plate, the bar formed

integral therewith and extending across the opening in said frame, the wiping material extending under said bar and over the sides of said frame, as set forth.

In testimony whereof I affix my signature 15 in presence of two witnesses.

ISRAEL KINNEY.
